UNITED STATES PATENT OFFICE.

WILLIAM H. RICHARDS, OF PHILADELPHIA, PENNSYLVANIA.

REVERSIBLE SHIRT.

1,275,090.

Specification of Letters Patent.

Patented Aug. 6, 1918.

Application filed June 24, 1916. Serial No. 105,594.

To all whom it may concern:

Be it known that I, WILLIAM H. RICHARDS, a citizen of the United States, residing at Philadelphia, in the county of Philadelphia and State of Pennsylvania, have invented new and useful Improvements in Reversible Shirts, of which the following is a specification.

The invention relates to apparel and more particularly to garments such as shirts, waists and the like, and has for an object to provide a garment of this character which, when soiled, can be quickly reversed; or in the use of which a new pattern can be presented by reversing the garment.

Among other features the invention comprehends a shirt which when one side becomes soiled is entirely reversed to present a new and clean surface of the body of the shirt, the bosom and the cuffs; one in which there is not only presented a clean surface but, if desired, the design or pattern on one side of the shirt can be different from that on the other so that the reversal will make it appear as if an entirely new and clean shirt has been substituted for the one previously worn.

I am aware that garments have been used heretofore embodying reversible features, but in most of these instances the garments are only partly reversible as in reversing the bosom of a garment or the cuffs thereof. Further, in garments that are entirely reversible the manner of securing the bosom or front is cumbersome and results in a clumsy and awkward appearance of the bosom; also greatly inconveniencing the wearer. Still further, in the reversal of a known garment the usual front hem of the bosom, which is commonly seen on all shirts worn by men, does not appear when the shirt is reversed and thus the effect of the bosom is entirely lost. In shirts provided with bosoms which have portions of the latter arranged to fold in order that a new and complete plait can be presented, great difficulty is found in laundering and the appearance is not the same as that of the neat flat hem in the ordinary shirt.

In the further disclosure of the invention, reference is to be had to the accompanying drawings constituting a part of this specification, in which similar characters of reference denote corresponding parts in all the views, and in which,

Figure 1 is a perspective view of my form of garment looking at the front thereof,

Fig. 2 is a perspective view of the same garment in its reversed position,

Fig. 3 is a horizontal sectional view taken 60 through the garment showing the arrangement of the plaits and the manner of closing the bosom of the shirt, and

Fig. 4 is a detail of one of the cuffs.

In the drawings the numeral 10 designates 65 broadly a man's shirt of that type whose bosom is divided into halves down the center of the front, and this shirt is composed throughout of material whose obverse 11 is herein shown as striped and whose reverse 70 12 is herein shown as plain, the idea being that the patterns on opposite faces are slightly different from each other, although of course this is not absolutely necessary. The numeral 13 is applied to the obverse or 75 striped face of one-half of the bosom, and the numeral 14 to the reverse or plain face of the other half of the bosom, which of course becomes the left hand half when the shirt is reversed as seen in Fig. 2 from the 80 position it initially occupied as seen in Fig.

1. As usual with shirts of this type, the meeting edges of the two halves of the bosom are hemmed where they lap each other and pierced with holes for the insertion of studs, 85 but in a reversible shirt made of material whose opposite faces differ in pattern care should be exercised in the formation of these hems so that the edges of the bosom may be lapped with the garment either side 90 out, and the pattern on the inner side will nowhere show on the outer. With this end in view, I fold the inner edge of one-half of the bosom backward to form the hem, and provide it with the usual lines of stitching, 95 and I fold the inner edge of the other half forward to form the hem and stitch it in the same manner. In Fig. 3 one-half 13 is shown folded forward as at 15, and the other half 14 is shown folded back as at 16. 100 The hems are then provided with holes 17 and 18 respectively for the insertion of the studs 19, and it is obvious that the holes should register so that the studs may be inserted whatever the position of the shirt. 105 If we assume that the front (or lower) face of the half 13 seen in Fig. 3 is striped as seen in Fig. 1, it will be obvious that when it is folded forward and hemmed as at 15 a part of the other face comes around into 110

view. The same may be said of the plain face of the half 14 when folded and hemmed as seen at 16. But that face of either half away from which the hem is folded has the pattern carried clear to the fold line, and therefore if the wearer desires his shirt bosom to present a consistent appearance, he has only to lap the hems against each other in either position of the shirt, and 10 insert the studs.

The cuff of the shirt is indicated by the numeral 20 and has a portion 21 foldable rearwardly upon a portion 22 with one face of the cuff designed or provided with a pattern harmonizing with the pattern of one 15 side of the shirt and its bosom and the other face of the cuff provided with a design or pattern harmonizing with the pattern on the other side of the shirt and its relative bosom 20 face. Thus when the shirt is reversed the cuffs are also reversed and the bosom faces and cuffs in each instance will harmonize in design with the design or pattern of the body of the shirt.

25 As mentioned heretofore each bosom face has its particular hem and the buttons used to close the bosom are common to both hems so that a separate lacing or fastening for the reverse bosoms when the shirt is reversed, is not necessary, and therefore my 30 invention does away with the clumsy appearance that the shirt would otherwise present at the bosom and further does not 35 inconvenience the wearer. If desired, the shirt can be plain white on both sides and

the bosom made correspondingly, although it will be understood that when the material is provided with a pattern or design the design can be the same on both sides or of different colors or configurations, as desired. 40

With this construction it will be seen that particularly at the neck-band of the garment, the overlapping plies of the material of the shirt will not be increased or thickened, whereas in garments having removable 45 and reversible bosoms, there is necessarily provided additional thicknesses of the material not only to obtain some semblance to the ordinary shirt but in order that the bosom when applied will be rigidly held 50 against slipping down upon the garment.

Thus with my improved form of shirt the same when in use will not show or in any manner indicate to the observer that the garment or bosom is reversible and by having 55 the novel features mentioned the garment will not inconvenience the wearer.

Having thus described the invention, I claim:—

A reversible shirt bosom having one pattern on the obverse and another on the reverse and divided into halves, the inner edge of one half being folded back and hemmed and that of the other half folded forward and hemmed, and unitary means for fastening the hems in contact with each other when the halves are overlapped to close the bosom. 60

In testimony whereof I affix my signature.
WILLIAM H. RICHARDS.
